UNITED STATES PATENT OFFICE.

ARTHUR HESS, OF LOS ANGELES, CALIFORNIA, ASSIGNOR OF ONE-HALF TO SAMUEL L. MAESH, OF LOS ANGELES, CALIFORNIA.

BRACKET-HANGER BACKING.

Application filed March 23, 1925. Serial No. 17,690.

To all whom it may concern:

Be it known that I, ARTHUR HESS, a citizen of the United States, and resident of Los Angeles, in the county of Los Angeles, State of California, have invented new and useful Improvements in a Bracket-Hanger Backing, of which the following is a specification.

This invention relates to a backing 10 adapted to be concealed in partitions, walls, and like places. It is the primary object thereof to provide a support for room fixtures, for illustration, plumbing fixtures. The support embodied in the present invention is arranged to be attached to some strong, durable, component of the building.

Plumbing fixtures are commonly mounted upon bolts, hangers, supports, and like devices which are secured in and to the walls 20 or partitions of the building. Many of these walls are built of material which is soft and does not offer sufficient strength to withstand the strain placed thereon by the weight of the fixture. The result is that the support pulls out of the wall with resultant damage. Another object of this invention 25 is to provide a support which is adjustable to the fixture or hanger requirements and also to the character of the building component to which it is attached.

These objects together with other objects and corresponding accomplishments are obtained by means of the embodiment of my invention illustrated in the accompanying 35 drawing, in which:

Fig. 1 is an elevation of a complete backing, showing how it would be mounted upon a vent pipe, the latter being shown in dot and dash lines; Fig. 2 is a plan view; Fig. 40 3 is a section as seen on the line 3—3 of Fig. 1; and Fig. 4 is a vertical section through a wall equipped with my improved backing and having a lavatory supported thereby.

Referring more particularly to the drawing, the backing comprises a rectangular frame comprising an upper or hanger bar 5, a lower bar 6, and side bars 7. As the side bars are the same in structure, it will only be necessary to describe one. The bars 45 are preferably of metal and may be of any desired shape. Bar 6 has holes 8 extending therethrough and adapted to receive the shanks of bolts. The side bars 7 have bolt holes spaced throughout the length thereof.

In the present instance, the side bars are 55 shown as formed of angle irons, but it is obvious that the invention is not limited to this particular shape.

The bar 5 is provided at the ends with slide members 10 to permit the bar to be 60 moved upwardly or downwardly upon the side bars. In the slides are elongated bolt holes 11 arranged to be registered with the holes 9. Bolts 12 extend therethrough for fastening the upper bar 5 to the side bars. 65 The structure is such as to provide for comparatively fine adjustment of the position of the top bar 5 on the frame. Initial adjustment is made by selecting proper bolt holes 9 upon the side bars and final adjustment by means of the elongated bolt holes 70 11 in the hanger bar.

The hanger bar is provided with holes 13 adapted to receive the shanks of bolts. Extending longitudinally of the hanger bar is 75 a rail 14 formed of suitable straps shaped to provide an undercut channel or slot for the passage therethrough of the shanks of bolts or like members. The channel is large enough to receive the heads of the bolts. 80 Bolts of this shape are indicated by 16. It is obvious that bolts 16 may be moved along the hanger bar to any position desired.

Suppose the fixture to be hung or supported by the backing is a lavatory, indicated by 17 in Fig. 4. The usual vent pipe therefor is indicated by 18 and is disposed within the wall. Such a vent pipe will serve as a suitable support for the backing. Before the walls are finished or plastered, 90 the backing is placed in position on the vent pipe by embracing the latter with U-bolts 19 and 20, these bolts being passed through selected bolt holes in bars 5 and 6. Bar 5 is adjusted in position upon the side bars 95 as may be desired for the particular case. The usual bracket hanger 20 or a templet therefor is disposed in its ultimate position to locate the proper position of bolts 16. These bolts are then locked in their position, 100 and the job is ready for the plasterers. When they have completed their work the only visible portion of the backing is the projecting bolts 16. In finishing the job, the bracket hanger 20 is placed over the bolts 105 and is secured in position thereon by the bolt nuts. The lavatory can then be hung in position. The fixture is thus supported by

the backing rather than by the wall. Repair or readjustment of the bracket is easy, especially as to the position of the bolts 16.

The plaster or finish may be removed so as to permit the bolts to be adjusted. The bracket hanger when in position covers the disturbed portion of the finish.

What I claim is:

1. A backing of the character described comprising a rectangular frame formed of bars having a hanger bar adjustably mounted on the intersecting bars so as to be movable to and from the parallel bar and provided with an elongated slot, means on the hanger bar for securing said frame to a supporting member, means on said parallel bar for securing said frame to said supporting member and bolts in said slot with their shanks extending forwardly therethrough.
2. A backing as specified in claim 1 characterized by the elongated slot in said hanger bar being formed by an undercut channel extending longitudinally of the hanger bar, and said bolts being mounted with their heads in said channel.
3. A backing of the character described comprising a rectangular frame provided with side bars having bolt holes spaced longitudinally, a hanger bar mounted on said

side bars for lateral adjustment, said hanger bar having elongated bolt holes for registration with said first mentioned bolt holes and being provided with a longitudinally extending undercut slot, and means for securing said frame to a supporting member.

4. A backing as specified in claim 3 characterized by said means comprising a U-bolt and said frame having bolt holes to receive the legs of said U-bolt.

5. In a backing of the character described, the combination of a rectangular frame provided with side bars having bolt holes spaced longitudinally, a hanger bar mounted on said side bars for lateral adjustment, said hanger bar having elongated bolt holes for registration with said first mentioned bolt holes and being provided with a longitudinally extending undercut slot, bolts to secure said hanger bars to said side bars, means for securing said frame to a supporting member, and bolts mounted with their heads in said slots and their shanks extending therethrough.

In witness that I claim the foregoing I have hereunto subscribed my name this 12th day of March, 1925.

ARTHUR HESS.
